UNITED STATES PATENT OFFICE

PAUL V. WHITNEY, OF COLUMBUS, OHIO, ASSIGNOR TO THE JEFFREY MANUFACTURING COMPANY, OF COLUMBUS, OHIO, A CORPORATION OF OHIO

EXTENSIBLE RAIL, PARTICULARLY FOR TROLLEY CONVEYER SYSTEMS

Application filed September 19, 1931. Serial No. 563,831.

In trolley conveyer systems wherein trolleys connected by a flexible draft device are adapted to travel along a trackway, it becomes necessary to tension the draft device to take up slack developed through wear of the parts. Elongation of the draft device naturally requires similar elongation of the trackway and it is the object of the present invention to provide an extensible rail of simple construction which will permit of elongation of the trackway without impairing its continuity.

According to the embodiment of the invention to be described, the trackway is made up of I-beams having their webs vertically disposed so that the top surfaces of their lower flanges are adapted for running engagement by the trolley wheels. Adjacent I-beam sections are mounted for relative displacement and telescoping means are provided for bridging a gap, occurring through adjustment, between the lower flanges of the sections, the bridging means being preferably flush with the top surfaces of the flanges and also with the lateral edges of the latter and possessing great strength and rigidity.

In applying the invention in practice, a substantially U-shaped track section is supported on a carriage which also supports a guide wheel for the draft device which is trained about the wheel with its runs lying beneath the U-shaped track section. The carriage is influenced by a counter-weight, so that the draft device is constantly tensioned and slack taken up, the U-shaped track section at the same time being displaced to elongate the trackway concomitantly with the elongation of the draft device, the bridging means coming into play to maintain the continuity of the trackway. The extensible rail of the present invention, however, may be utilized in other appropriate combinations and consequently I, of course, do not limit myself in this respect.

In the drawings:

Figure 1 is a plan view of the carriage and the supporting means therefor.

Figure 2 is a side elevation of the devices shown in Figure 1.

Figure 3 is a section on line 3—3 of Figure 2.

Figure 4 is an elevation of the telescopic portion of the track showing the ends of the relatively movable sections in spaced relation.

55

Figure 5 is a plan view partly in section of the track portion shown in Figure 4, and

Figure 6 is a plan view partly in section of the telescoping track portion with the relatively displaceable sections substantially in contact.

60

Referring to the drawings, reference numeral 10 designates generally a rectangular frame supporting at its corners pairs of flanged wheels 11 and 12, which project into the channels of channel bars 13 and 14 to travel on the lower flanges of the latter which are horizontally disposed. The channel bars are suitably braced and supported through cross members 15, 16, 17 and 18. Between members 15 and 16 a pair of brackets 17' and 18' revolvably support a sheave 19, over which is trained a cable 20, whose upper end is fastened to the frame 10 as at 21 and to whose lower end is connected a counter-weight 22, Figure 2.

70

Bars 23 and 24 extending longitudinally of the frame 10 have secured thereto a plate 25 which supports a downwardly projecting stud shaft 26 upon which is revoluble a sprocket wheel 27. Also a U-shaped I-beam section 28 is secured to members 23 and 24 with its curved portion lying directly above the periphery of the sprocket wheel, the web of the I-beam being vertical.

85

I-beam sections 29 and 30 are supported externally of carriage 10 in continuation of the parallel portions of the U-shaped track section. As here shown, the ends of sections 29 and 30 are secured beneath member 18, which connects the ends of channels 13 and 14. With the carriage at its right hand limit of travel, Figures 1 and 2, the ends of section 28 are in contact with the ends of sections 29 and 30 and the lower flanges of the sections form a continuous trackway for the trolley wheels 31 and 32. The trolleys 33 are connected by means of sprocket chain 34, which is engaged by sprocket wheel 27 and from the description thus far, it will be evi-

90

95

100

dent that counter-weight 22 exerts continuous tension on the sprocket chain and as slack develops in the latter, carriage 10 moves to the left, causing a gap to exist between the ends of section 28 and sections 29 and 30. To bridge the gap thus formed the following is provided:

To the ends of section 28 and in longitudinally projecting relation thereto are secured 10 bars 35 and 36 of exactly similar form. The bar 36 is particularly shown in Figures 3 to 6 and consequently will be described. Referring then to Figures 3 to 6, bar 36 which is secured beneath the flanges of section 28 15 and which is preferably equal in width to the width of the flanges is provided on its top lateral margins with parallel ribs 37 and 38, which are adapted to serve as guide members for the end of section 30. The lower flanges 20 39 and 40 of section 30 are provided adjacent the ends of the latter with longitudinally extending recesses 39' and 40', so that the recessed end of the section is adapted for reception between ribs or guide members 37 25 and 38 with a sliding fit. As may be seen from Figure 3, the inner faces of the ribs are undercut and the edges of the recessed flange portions have a mating conformation, so that the parts may be said to form 30 a dove-tailed joint. Due to the form of the joint, the bar 36 serves to retain sections 28 and 30 in strict alignment.

It will be further noted that the tops of the ribs are substantially flush with the top surfaces of the flanges, Figure 3, so that, as shown, the tread comprises inner and outer portions constituted by the flanges and ribs respectively. Between the ends of the ribs and the inner ends of recesses 39' and 40' 35 the tread will be constituted solely by the narrowed flange portions and between the ends of the I-beam sections solely by ribs 37 and 38. Since the ribs and narrowed flange portions are complementary, it will be 40 evident that the trolley wheels can travel on both or pass from one to the other without shock. Also, since the lateral dimension of the bar is the same as the lateral dimension 45 of the full lower flanges, no change in the form of trolley hanger is necessitated.

It will be understood that various modifications of the described structures are possible without departure from the scope of the invention as defined in the following claims 50 and while I have shown and described my extensible rail in a particular installation, it is to be understood that I do not limit myself in this respect.

I claim:

60 1. An extensible rail for trolley conveyors, said rail comprising I-beam sections in end to end relation with their webs substantially vertically disposed, means for supporting said sections for relative displacement, and 65 means for bridging a gap between the lower

flanges of the sections comprising parallel guide members fixed to one of said sections to project longitudinally thereof and between which the lower flanges of the other section are received with a sliding fit, the tops of the guide members being substantially flush with the top surfaces of said flanges. 70

2. An extensible rail for trolley conveyors, said rail comprising I-beam sections in end to end relation with their webs substantially vertically disposed, means for supporting said sections for relative displacement, and means for bridging a gap between the lower flanges of the sections comprising parallel guide members fixed to one of said sections to project longitudinally thereof and between which the lower flanges of the other section are received with a sliding fit, the tops of the guide members being substantially flush with the top surfaces of said flanges, 75 the end portions of the flanges of said other section being longitudinally recessed, the distance between the outer edges of the guides being the same as the transverse dimension of the full flanges. 80

3. An extensible rail for trolley conveyors, said rail comprising I-beam sections in end to end relation with their webs substantially vertically disposed, means for supporting said sections for relative displacement, and means for bridging a gap between the lower flanges of the sections, said means comprising a bar fixed in longitudinally projecting relation beneath one of said sections and provided on its top with parallel ribs between which the lower flanges of the other section are received with a sliding fit. 85

4. An extensible rail for trolley conveyors, said rail comprising I-beam sections in end to end relation with their webs substantially vertically disposed, means for supporting said sections for relative displacement, and means for bridging a gap between the lower flanges of the sections, said means comprising a bar fixed in longitudinally projecting relation beneath one of said sections and provided on its top with parallel ribs between which the lower flanges of the other section are received with a sliding fit, the tops of the ribs being substantially flush with the top 100 surfaces of said flanges. 105

5. An extensible rail for trolley conveyors, said rail comprising I-beam sections in end to end relation with their webs substantially vertically disposed, means for supporting said sections for relative displacement, and means for bridging a gap between the lower flanges of the sections, said means comprising a bar fixed in longitudinally projecting relation beneath one of said sections and provided on its top with parallel ribs between which the lower flanges of the other section are received with a sliding fit, the ribs having portions overlying the edges of the flanges of said other section. 110 120 125 130

6. An extensible rail for trolley conveyers, said rail comprising I-beam sections in end to end relation with their webs substantially vertically disposed, means for supporting said sections for relative displacement, and means for bridging a gap between the lower flanges of the sections, said means comprising a bar fixed in longitudinally projecting relation beneath one of said sections and provided along its top longitudinal margins with parallel ribs, the flanges of the other section being longitudinally recessed and received between said ribs with a sliding fit, the width of said bar being the same as the width of the full flanges.

7. An extensible rail for trolley conveyers, said rail comprising I-beam sections in end to end relation with their webs substantially vertically disposed, means for supporting said sections for relative displacement, and means for bridging a gap between the lower flanges of the sections, said means comprising a bar fixed in longitudinally projecting relation beneath one of said sections and provided along its top longitudinal margins with parallel ribs, the flanges of the other section being longitudinally recessed and received between said ribs with a sliding fit, the width of said bar being the same as the width of the full flanges, the inner faces of the ribs being undercut and the edges of the recessed flange portions mating therewith.

8. An extensible rail for trolley conveyers, said rail comprising I-beam sections in end to end relation with their webs substantially vertically disposed, means for supporting said sections for relative displacement, and means for bridging a gap between the lower flanges of the sections, said means comprising a bar fixed in longitudinally projecting relation beneath one of said sections and provided along its top longitudinal margins with parallel ribs, the flanges of the other section being longitudinally recessed and received between said ribs with a sliding fit, the width of said bar being the same as the width of the full flanges, the inner faces of the ribs being undercut and the edges of the recessed flange portions mating therewith, the tops of the ribs being substantially flush with the top surfaces of said flanges.

9. An extensible rail for trolley conveyers, said rail comprising I-beam sections in end to end relation with their webs substantially vertically disposed, means for supporting said sections for relative displacement, and means for bridging a gap between the lower flanges of the sections comprising parallel guide members fixed to one of said sections to project longitudinally thereof and between which the lower flanges of the other section are received with a sliding fit, the top surfaces of said guide members comprising lateral continuations of the top surfaces of the

flange portions engaged between the guide members.

10. An extensible rail for trolley conveyers, said rail comprising I-beam sections in end to end relation with their webs substantially vertically disposed, means for supporting said sections for relative displacement, and means for bridging a gap between the lower flanges of the sections comprising parallel guide members fixed to one of said sections to project longitudinally thereof and between which the lower flanges of the other section are received with a sliding fit, the end portions of the flanges of said other section being longitudinally recessed and the guide members being complementary to the recessed flange portions to render the longitudinal lines of the sections substantially unbroken.

In testimony whereof I affix my signature.

PAUL V. WHITNEY.
